MACHINE KEY EXTRACTOR

Gustave A. Burstrom, New York, N. Y.

Application November 5, 1941, Serial No. 417,950

5 Claims. (Cl. 29—86.1)

This invention relates to a tool of very simple construction for pulling keys from machine parts, such as from pulleys and shafts or gears and shafts, and which is principally adapted for use for pulling plain keys or keys from which the gibs or teeth have been broken off, and which can therefore not be readily pulled with other types of tools.

More particularly, it is an aim of the invention to provide an improvement on the old conventional type of key chisel by the provision of a flexible joint or knee between the handle of the tool and the sharpened end of the tool bit or head.

Other objects and advantages of the invention will hereinafter become more fully apparent from the following description of the drawing, which illustrates a preferred embodiment of the invention, and wherein—

Figure 1 is a side elevational view of the tool,

Figure 2 is a fragmentary front elevational view of the bottom part thereof,

Figure 3 is a longitudinal sectional view taken substantially along the plane of the line 3—3 of Figure 1, and

Figure 4 is a longitudinal sectional view taken substantially along the plane of the line 4—4 of Figure 2, and showing the tool in an applied position.

Referring more particularly to the drawing, wherein like reference characters designate like or corresponding parts throughout the different views, 10 designates generally the improved key extractor or puller, and which includes an elongated handle 11 having on one side of an end thereof an apertured ear or extension 12. The opposite side of the end of the handle 11, provided with the extension 12, is recessed at 13 to receive an elongated plate 14 which is detachably secured thereto by fastenings 15, and which is provided with an outer free end 16 forming an apertured ear, corresponding to the ear 12. The ears 12 and 16 combine to form a bifurcated end 17 of the handle 11, and the apertures of said ears are disposed in alignment to receive trunnions 18 which project from opposite sides of the inner, enlarged end 19 of the head or bit 20 of the tool 10. The end 19 is provided with a rounded portion 21, as seen in Figure 4, which bears against an inwardly bowed portion 22 of the handle 11. The rounded portion 21 is provided with a shoulder 23 at one end thereof, and the inwardly bowed portion 22 is provided with a shoulder 24 which is disposed to face and be engaged by the shoulder 23. The head 20 is tapered from its enlarged end 19 to

toward its opposite, free end and is beveled on its inner side and at its free end to form a chisel-like edge 25.

A leaf spring 26 has one end fastened by means of fastenings 27 to the handle 11. The opposite, free end 28 of the spring 26 is bent outwardly and is disposed to bear against the inner side of the head or bit 20 for urging said bit to swing outwardly and toward an extended position. The movement of the head or bit 20 toward an extended position relatively to the handle 11 is restricted by engagement of the shoulder 23 with the shoulder 24, as seen in Figure 1, so that when the bit 20 is in an extended position relatively to the handle 11 it is disposed substantially at an oblique angle thereto.

For the purpose of illustrating the application and use of the tool 10, in Figure 4 a portion of a pulley or gear is indicated at 29, a portion of a shaft, on which the pulley or gear 29 is mounted, is indicated at 30, and a key is shown at 31 for connecting the parts 29 and 30. To apply and operate the tool 10, the edge 25 of the head 20 is positioned against the key 31 and the rounded outer side 32 of the head 20 is disposed against the side of the gear or pulley 29 from which the key 31 projects. By then pushing downwardly on the handle 11 the edge 25 will be caused to bit into the top surface of the key 31 and the rounded portion 32 will ride downwardly against the aforementioned side of the gear or pulley 29, thereby causing the bit 20 to swing relatively to the handle 11 and against the action of the spring 26 for forcing the key 31 outwardly of the pulley or gear 29. The pressure exerted by the handle 11 on the head 20 will be borne by the contacting surfaces 21 and 22 so that none of the force will be exerted directly on the trunnions 18. The previously described operation for extracting the key 31 can be repeated as many times as is necessary to completely extract the key.

Various modifications and changes are contemplated and may obviously be resorted to, provided they fall within the spirit and scope of the invention as hereinafter defined by the appended claims, as only a preferred embodiment of the invention has been disclosed.

I claim as my invention:

1. A machine key extractor comprising a handle, a head pivotally connected to one end of said handle, said head having a rounded bearing surface adjacent one end and a sharpened free end adapted to engage and penetrate the surface of a key to be pulled and a rounded surface remote from said free end for bearing engagement with

a part fastened by the key and at a different elevation from the sharpened free end, means for yieldably urging the head toward an extended position relatively to the handle, and means for restricting the swinging movement of the head, toward an extended position, and combining with said first mentioned means for normally positioning said sharpened free end longitudinally outwardly beyond the pivot or axis of the head and the head at an oblique angle to the longitudinal axis of the handle with said sharpened free end lowermost.

2. A key extractor comprising an elongated handle member, a head pivotally connected to one end of said handle member and having a rounded outer side adapted to bear against a gear or pulley from which a key is to be pulled, said head being provided with a sharpened free end adapted to penetrate the key to be pulled as the head rocks on said outer side, means for yieldably urging the head toward an extended position, and stop means for restricting the swinging movement of the head toward an extended position with said sharpened free end lowermost.

3. A key extractor comprising a handle having a bifurcated end, a head having a portion disposed between said bifurcated end, means for pivotally connecting the head to the bifurcated end, 5 said head having a rocker surface and being provided at its lowest point with a sharpened free end adapted to engage and penetrate a key to be pulled as the head rocks on said surface, means for yieldably urging the head toward an extended position relatively to the handle, and stop means for limiting the movement of the head toward said extended position.

10 4. A tool as in claim 3, said yieldable means comprising spring means carried by the handle for engaging and yieldably urging the head toward an extended position relatively to the handle.

15 5. A tool as in claim 3, said yieldable means comprising a leaf spring having an end fastened to the handle, the opposite, free end of the leaf spring being disposed to bear against the head for urging it toward an extended position.

GUSTAVE A. BURSTROM.
